US00D578012S

(12) **United States Design Patent**
Friedland et al.

(10) **Patent No.:** **US D578,012 S**
(45) **Date of Patent:** **** Oct. 7, 2008**

(54) **THERMOFORM BOTTOM WITH
PLACEMENT**

(75) Inventors: **Jason Friedland**, Franklin, TN (US);
Angel Hernanadez, Nolensville, TN (US); **Rebecca Morgan Valentine**, Franklin, TN (US); **Peter Slusarczyk**, Nolensville, TN (US)

(73) Assignee: **MARS, Incorporated**, McLean, VA (US)

(**) Term: **14 Years**

(21) Appl. No.: **29/287,520**

(22) Filed: **Aug. 17, 2007**

(51) LOC (8) Cl. **09-05**

(52) U.S. Cl. **D9/707**

(57) **CLAIM**

The ornamental design for a thermoform bottom with placement.

DESCRIPTION

FIG. 1 is a perspective view of a thermoform bottom with placement showing our new design;

FIG. 2 is a top view thereof;

FIG. 3 is a bottom view thereof;

FIG. 4 is a left side view thereof;

FIG. 5 is a front view thereof; and,

FIG. 6 is a rear view thereof.

The broken lines shown in the drawings are for illustrative purposes and form no part of the claimed design.

UNITED STATES PATENT AND TRADEMARK OFFICE
CERTIFICATE OF CORRECTION

PATENT NO. : Des. 578,012 S
APPLICATION NO. : 29/287520
DATED : October 7, 2008
INVENTOR(S) : Jason Michael Friedland et al.

Page 1 of 1

It is certified that error appears in the above-identified patent and that said Letters Patent is hereby corrected as shown below:

Title Page, Item (75) Inventors:

Delete the second inventor's last name incorrectly shown as "HERNANADEZ" and insert --HERNANDEZ--.

Signed and Sealed this

Twenty-third Day of December, 2008

JON W. DUDAS
Director of the United States Patent and Trademark Office
